Filed Feb. 28, 1974, Ser. No. 446,614

Term of patent 14 years

Int. Cl. D6—04

U.S. Cl. D6—154

FIG. 1 is a front and left side perspective view of a literature display rack showing my new design;

FIG. 2 is a rear and right side perspective view with the front access door in opened position;

FIG. 3 is a left side elevational view of the rack in the condition of FIG. 1;

FIG. 4 is a top plan view thereof;

FIG. 5 is a bottom plan view thereof;

FIG. 6 is a left side elevational view of a second embodiment of a literature display rack showing my new design wherein the rack differs from that shown in FIGS. 1-5 only in that the rear is identical to the front shown in FIG. 1 except for the absence of the lower access door;

FIG. 7 is a front elevational view of a third embodiment of a literature display rack showing my new design wherein the rack differs from that shown in FIGS. 1-5 only in that the left side rack is similar to the top rack shown in FIG. 1 but is approximately one-third as wide;

FIG. 8 is a front elevational view of a fourth embodiment of a literature display rack showing my new design wherein the rack differs from that shown in FIG. 7 only in that the right side is identical to the left; and

FIG. 9 is a rear elevational view of a fifth embodiment of a literature display rack showing my new design wherein the sides and front are identical to the rack shown in FIG. 8.

I claim:

The ornamental design for a literature display rack, as shown and described.
